UNITED STATES PATENT OFFICE.

HENRY SIEDENTOP, OF JERSEY CITY HEIGHTS, NEW JERSEY.

DESIGN FOR CURTAIN-BANDS.

Specification forming part of Design No. **11,146**, dated April 8, 1879; application filed February 14, 1879.
[Term of patent 7 years.]

To all whom it may concern:

Be it known that I, HENRY SIEDENTOP, of Jersey City Heights, county of Hudson, and State of New Jersey, have invented a new and original Design for Curtain-Bands, of which the following is a full, clear, and exact description, reference being had to the accompanying drawing making part of this specification, in which my improved curtain-band is shown in perspective view.

The object of my invention is to improve the well-known gimp bands that are employed for supporting curtains of all kinds in such a manner that their monotonous appearance is done away with, and a more ornamental and striking character imparted to the same.

The invention consists of a curtain-band having one or more colored ribbons that are drawn in longitudinal direction through the pillars of the middle portion, so as to pass alternately above and below the same.

Referring to the drawing, A represents a curtain gimp band of the usual construction, which is bound off at the middle portion by means of connecting side bands, a, which are woven longitudinally along both ends of the middle portion. That portion of the middle portion between the connecting-bands is ornamented by one or more ribbons, B, of silk or other material, and of any color, that form a suitable contrast with the color of the gimp

band. The ribbon or ribbons B are drawn through between the pillars b of the middle portion in such a manner that they pass alternately from the lower side of one or more pillars to the upper side of the adjoining pillars, and so on. The ribbons are, at the ends, connected with or bound off in any suitable manner at the loops C, by which the curtain-band is suspended.

By the ribbon or ribbons the entire character of the curtain-band is changed from the plain and monotonous appearance of the old styles of bands to one of peculiar brightness and neatness, these bands admitting, furthermore, the easier matching of the same with curtains of different colors and patterns.

Having thus described my invention, I claim as new and desire to secure by Letters Patent—

The design for a curtain-band, consisting of side bands, a, and pillars b, the latter alternating with exposed portions of one or more center bands, B, substantially as shown and described.

In testimony that I claim the foregoing as my invention I have signed it this 8th day of February, 1879.

HENRY SIEDENTOP.
